UNITED STATES PATENT OFFICE

ALFRED F. HELIN, OF WATERTOWN, NEW YORK, ASSIGNOR TO THE BAGLEY AND SEWALL COMPANY, OF WATERTOWN, NEW YORK, A CORPORATION OF NEW YORK

WIRE-WASHING DEVICE FOR PAPER-MAKING MACHINES

Application filed January 5, 1928. Serial No. 244,572.

This invention relates to certain improvements in wire washing devices designed for use on a Fourdrinier paper making machine for cleaning the making wire.
5 The Fourdrinier paper making machines employ an endless wire onto which the stock is flowed from a headbox, this wire acting to form the stock into the paper web or sheet. A certain amount of stock clings to the mesh 10 of the wire and it is desirable that this stock be removed from the wire as the wire returns from the couch roll to the breast roll, at which latter point the stock is flowed onto the wire in making the web.

15 Various spray or water shower devices have been suggested, which are disposed so as to direct the water against the wire, and such devices will clean the wire where a sufficient quantity and pressure of water is available.
20 In paper making machine practice, however, the water which it is desirable to use for this wire cleaning purpose is what is known as white water, which is taken from the stock circulating system. The amount of this white 25 water is limited and it is therefore necessary to economize in the use of this white water.

The special object of the present invention is to produce an improved spray nozzle which will deliver the water in a flat spray across 30 the wire, this water being delivered in substantially a straight line of substantially uniform pressure across the wire. This has been effected by the use of a nozzle of peculiar form and shape, which forms the important 35 feature of this invention.

With this and other objects not specifically referred to in view, the invention consists in certain novel parts, arrangements and combinations which will be described in 40 the accompanying drawings showing a preferred embodiment of the invention and the novel features will then be pointed out in the claims hereunto annexed.

In these drawings—

45 Figure 1 is a diagrammatic, partly broken away, side elevation of so much of a Fourdrinier machine as is necessary for an understanding of the invention;

Figure 2 is a partly sectional, partly broken away view of the improved sprayer, the

view being taken in the direction of arrow 2 of Figure 1;

Figures 3 and 4 are enlarged detail sectional views of one of the nozzles, Figure 3 being taken on line 3—3 of Figure 2 and Figure 4 being taken on line 4—4 of Figure 3;

Figure 5 is an enlarged detail view of the spray pipe, the view being taken in the direction of arrow 5 of Figure 2, and

Figure 6 is a detail view showing the spray, 60 looking at it edgewise.

Referring now to these drawings, the usual Fourdrinier machine has been diagrammatically indicated, including suitable framing 1, 2, a breast roll 3 and a couch roll 4. The making wire is indicated at 5, this making wire passing over the usual table rolls 6 and suction boxes 7. The wire in its travel passes from the breast roll 3 around the couch roll 4 and back to the breast roll.

In accordance with the invention, a sprayer device of novel and improved construction has been provided for directing a steady and uniform spray against the wire as it returns from the couch roll to the breast roll, this sprayer being indicated generally by the numeral 8 in Figure 1. In accordance with the invention, an improved spray nozzle has been provided which will effect a maximum spraying or cleaning action on the wire with a minimum amount of water used. While the specific construction of this spray nozzle may be varied to a certain extent, there is provided a nozzle pipe provided with peculiarly formed nozzles or spray orifices which, because of 80 their shape, may be located at considerable distances apart, and which act to form a flat spray, this spray striking the wire at a substantially uniform pressure across the width of the wire.

It has been found in practice that this sprayer will effect a suitable cleaning of the wire and at the same time will effect a great economy in the amount of water used, so that the white water from the stock circulating system may be used. As shown, the sprayer includes a spray pipe 9 connected to a supply pipe 10 to which white water is supplied from any suitable point in the stock circulating system. This spray pipe is provided, on one 100

side, with a number of spray nozzles or orifices 11, these being, as shown, located at considerable distances apart in the pipe. The spray produced by these nozzles is that indicated in Figures 2 and 6, that is, it is a flat spray, being very thin, as viewed edgewise, as shown in Figure 6, and spread widthwise, as shown in Figure 2, so as to form a substantially continuous spray across the length of

10 the wire, the pipe 9 being located a suitable distance from the wire so that the water from the nozzles meet at the wire, as shown in Figure 2, to form a substantially continuous spray.

15 Referring to Figure 3, it will be observed that the walls of the orifices are shaped so that they contract from the inside of the pipe 9 to the outside, as indicated at 12, thus acting to form the thin edge spray across the wire of Figure 6. Referring to Figure 4, however, it will be seen that the orifices considered longitudinally of the pipe widen from the inside of the pipe to the outside, as indicated at 13, this shape of the nozzle causing the formation of the fan-like spray shown in Figure 2. Referring to Figure 5, it will be observed that the outer rim of the orifices is an ellipse, this shape having been found to give a more uniform pressure of the spray

20 widthwise of the wire at the point where it strikes the wire.

25 The nozzle is conveniently formed by first drilling a hole in the pipe of a convenient size, which hole is then reformed by means of a suitable tool which will give the desired shape to the nozzle.

30 It will be understood that the shape, the size and the spacing of the orifices depend on the pressure used and the distance of

40 the spray pipe from the wire, these parts being so arranged as to effect the spraying action in a thin line of substantially uniform pressure across the width of the wire.

45 While the invention has been shown and described in its preferred form, it will be understood that certain changes and variations may be made in the particular construction and arrangement of the parts without departing from the invention as defined in

50 the appended claims.

What I claim is:

1. In a Fourdrinier paper making machine, the combination of the making wire, a spray pipe extending across the wire for directing wash water against the wire, and spaced nozzles or orifices formed in the wall of the pipe, the walls of which orifices converge transversely of the pipe.
2. In a Fourdrinier paper making machine, the combination of the making wire, a spray pipe extending across the wire for directing wash water against the wire, and spaced nozzles or orifices formed in the wall of the pipe, the walls of which orifices converge

transversely of the pipe, and the outlet ends of which are elliptical lengthwise of the pipe.

In testimony whereof, I have hereunto set my hand.

ALFRED F. HELIN.
